PROPELLER

Lee Barton Williams, Pittsburgh, Pa.

Application July 21, 1939, Serial No. 285,780

2 Claims. (Cl. 230—122)

This invention relates to new and improved means for propelling aeroplanes and other vehicles, one of the objects being to provide a novel arrangement of propeller blades shiftable about radial axis at the will of the operator and located within a compression chamber into which the blades operate to suck the air and compress it so that it will be expelled under high pressure through an outlet disposed oppositely to the inlet.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

In the accompanying drawings the preferred form of the invention has been shown.

In said drawings

Figure 1 is a central vertical longitudinal section through the apparatus, the blades and their shaft being shown in elevation.

Figure 2 is a plan view of the structure shown in Figure 1.

Figure 3 is a section on line 3—3, Figure 1.

Figure 4 is a section on line 4—4, Figure 1.

Figure 5 is an enlarged section on line 5—5, Figure 1.

Figure 6 is an enlarged section on line 6—6, Figure 1.

Figure 7 is a section on line 7—7, Figure 1.

Referring to the figures by characters of reference, 1 designates a suitable base having standards 2 in which is journaled a tubular shaft 3 adapted to receive motion through any suitable mechanism. For example a sprocket 4 can be secured to one end of the shaft and driven by a chain 5. This sprocket and chain can be located in a suitable housing 6 provided therefor, access to the shaft and sprocket being attainable through an opening which is normally closed by a cover plate 7.

Shaft 3 is tubular and has longitudinal slots 8 through which extend connecting pins 9 radiating from a shank 10 mounted to slide within the shaft 3.

A split ring is mounted on shaft 3 and is engaged by the pins 9. This ring 11 extends between opposed pairs of rollers 12 extending toward each other from opposed arms of the forked end 13 of a lever 14. This lever is fulcrumed as at 15 and is adapted to be held in any posi-

tion to which it might be adjusted, by means of a toothed segment 16 and a pawl 17. Thus it will be noted that by swinging the lever 14 on its fulcrum the pairs of rollers 12 will thrust on the revolving ring 11 and cause it to shift 5 along shaft 3 and carry the shank 10 therewith without interfering with the rotation of the shaft.

Propeller blades radiate from the shaft 3 as indicated at 18 and are regularly spaced annularly 10 about the shaft. Each of these blades has a bearing stud 19 seated in the shaft 3 and also has a laterally extended arm 20 connected to a pin 21 by a link 20'. These pins are mounted to slide within slot 22 in shaft 3, and are extended from shank 10.

Obviously when the shank 10 is shifted longitudinally in one direction or the other, the arms 20 will be shifted simultaneously so that all of the blades 18 will be simultaneously turned in the 20 same direction and the same distance. Thus the displacement of air by the blades can be regulated at the will of the operator.

Located back of each of the blades 18 and spaced therefrom are supplemental blades 23. 25 These blades are joined to the blades 18 by tie-bolts 24 and suitable spacing means not shown. The outer ends of the blades 23 project beyond the corresponding ends of the blades 18 but the inner ends of blades 23 terminate at points spaced 30 from the shaft 3. Blades 23 are pitched at the same angle as the blades 18 to which they are joined. The outer ends of blades 18 are connected by a hoop 25 to which they are pivotally attached and another hoop 26 pivotally engaged 35 by the outer ends of the blades 23. As the blades 23 project outwardly beyond the ends of the blades 25, the two hoops are not located side by side and, therefore, when blades 18 are rotated about their individual radial axes and the blades 23 caused to swing about said axes, one hoop will not come against the other. Consequently there is always a clearance between the two hoops no matter to what position the blades may be adjusted and air is thus free to flow between the 40 hoops at all times. The inner ends of the blades 23 are spaced from shaft 3 in order that they may be free to swing about the axes of the blades 18 without interfering with the movement of the arms 20. The hoops serve to hold the blades 50 properly spaced at their outer ends without interfering with their angular adjustment about their longitudinal axes. It will be noted that while blades 18 turn about their individual axis, the blades 23 swing about these axes of the blades 18.

The propeller blades are located within a housing 27 provided at one side with an inlet 28 and at its opposite side with an outlet 29. The inlet and outlet are concentric with shaft 3 and each 5 is surrounded by an outwardly extended frusto-conical flue 30 which, in turn, contains concentric frusto-conical baffles 31 spaced apart so as to provide inwardly flared concentric air passages. Screens 32 can be located at the outer ends of the 10 flues 30 to prevent the admission of foreign matter.

In operation the shaft 3 is rotated at high speed and the action of the blades 18 and 23 is such as to draw the air through the inlet and expel 15 it through the outlet, the force thus exerted being sufficient to propel the vehicle to which the propellers are connected. The propellers will build up a compression within the housing 27 so that the air will be propelled from the outlet 20 under this increased pressure and thereby accelerate propulsion.

What is claimed is:

1. Apparatus of the class described including a stationary housing having an inlet and an outlet 25 oppositely disposed, a shaft extending through the inlet and the outlet and concentric therewith, means for driving the shaft, propeller blades radiating from the shaft and within the housing and mounted for rotation about their individual 30 longitudinal axes, means carried by the shaft and operable independently of the rotation of the shaft for simultaneously rotating the blades about their individual longitudinal axis, a hoop con-

necting the outer ends of said blades and pivotally engaged thereby, supplemental blades back of and parallel with the propeller blades and spaced therefrom, said supplemental blades and propeller blades being fixedly connected for movement together, and a hoop connecting the outer ends of the supplemental blades, said supplemental blades being extended outwardly beyond the outer ends of the propeller blades. 5

2. Apparatus of the class described including a stationary housing having an inlet and an outlet oppositely disposed, a shaft extending through the inlet and outlet and concentric therewith, means for driving the shaft, propeller blades radiating from the shaft and within the housing 15 and mounted for rotation about their individual longitudinal axes, means carried by the shaft and operable independently of the rotation of the shaft for simultaneously rotating the blades about their individual longitudinal axis, a hoop connect- 20 ing the outer ends of said blades and pivotally engaged thereby, supplemental blades back of and parallel with the propeller blades and spaced therefrom, said supplemental blades and propeller blades being fixedly connected for movement together, and a hoop connecting the outer ends of the supplemental blades, said supplemental blades being extended outwardly beyond the outer ends of the propeller blades, and inwardly flared concentric baffles within the inlet and outlet and co- 25 operating to provide inwardly flared concentric air passages opening into the housing. 30
